ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,208,580.

Specification of Letters Patent.

Patented Dec. 12, 1916.

Application filed June 22, 1915. Serial No. 35,499.

To all whom it may concern:

Be it known that I, ALFRED G. F. KUROWSKI, a subject of the German Empire, residing in Brooklyn borough, in the county of 5 Kings, city and State of New York, have invented certain new and useful Improvements in Type-Writing Machines, of which the following is a specification.

This invention relates to typewriting machines and more particularly to means for locking the printing mechanism of the machine against unauthorized operation.

The means for holding the printing mechanism inoperative may comprise a bar which 15 may be passed through an opening in the frame of the machine and across the machine directly beneath the key levers, and then projected through an opening at the other side of the machine.

20 The bar has a flange at one of its ends adapted to catch against the outside of the frame of the machine, since said flange or fluke is too large to go through the opening in the machine base through which the 25 bar passes. This bar may at its other end extend through the base at the opposite side of the machine, and may be sealed by a padlock having its staple extending through a hole in the end portion of the bar extending 30 from said other side of the machine frame. The padlock itself is too large to go through the opening in the machine base. The bar cannot be removed from the machine except by unlocking and withdrawing 35 the padlock, for the bar is prevented from moving in one direction by its flange and in the other direction by the padlock.

Other features and advantages will hereinafter appear. In the accompanying drawings, Figure 1 is a side elevation of an Underwood typewriter showing my invention as applied thereto. Fig. 2 is a fragmentary perspective view, showing the bar as rendering the printing mechanism inoperative, 45 the bar being locked to the machine. Fig. 3 is a perspective view of the locking bar.

In the Underwood typewriter, keys 1 are connected to type-bars 2 through interponents 3 to cause the types 4 to print characters on a work-sheet carried by a platen 5.

In order to hold the keys 1 and type-bars 2 locked against operation, a wooden bar 6 may be passed through the usual opening 7 in the frame 8 of the machine, beneath the 55 keys 1 and out through a similar opening 9

in the other side of the machine. The bar 6 rests on the lower edges of the openings, and fits snugly beneath the keys 1 thereby effectually locking the latter. It has at one end a fluke or barb in the form of a flange 60 10 extending from a metal band 11. The flange 10 lies against the outside of the frame 8 when the bar 6 is in position.

To prevent the other end of the bar 6 from being drawn through the machine, it 65 is provided, at a portion extending out of the opening 9 in the opposite portion of the frame 8, with a hole 12, through which the staple 13 of an ordinary padlock may be passed. The staple seals the bar 6 locked 70 in the machine, being too large to pass through the opening 9. The padlock may be unsealed or opened by a key, and the staple withdrawn, and the bar drawn out of the machine by the other end.

75 The bar 6 has a portion 14 cut away to clear certain mechanism of the machine.

The end of the holding bar 6 to which the lock is attached may be protected against injury by a metal band 15.

80 Variations may be resorted to within the scope of the invention, and portions of the improvements may be used without others.

Having thus described my invention, I claim:

85 1. In a typewriting machine, the combination with printing mechanism comprising type-bars and keys for operating said type-bars, of a bar in position to hold said printing mechanism against operation, said bar movable lengthwise into and out of said holding position.

90 2. In a typewriting machine, the combination with printing mechanism comprising type-bars and keys for operating said type-bars, of a bar to hold said printing mechanism against operation, said bar movable in the direction of its length and thereby removable from the machine, and means to lock the bar in the machine in position to hold the printing mechanism against operation.

95 3. In a typewriting machine, the combination with printing mechanism comprising type-bars and keys for operating said type-bars, of a bar extending transversely of the machine beneath the keys and adapted to hold said keys against operation, said bar movable in the direction of its length to release the keys, and means for preventing the 100 110

removal of said bar comprising a fluke or barb at one end of the bar, and a lock at the other end of the bar.

4. The combination with a frame and a key-lever mechanism contained therein comprising a set of key levers ranged across the frame, said frame having openings in its opposite sides, of a locking bar extending transversely of the frame and key levers beneath the key levers to lock the latter, and projecting through said openings and supported directly by the frame at said openings, said bar arranged to be withdrawn lengthwise to release the key levers.

15 5. The combination with a frame and a key-lever mechanism contained therein comprising a set of key levers ranged across the frame, said frame having openings in its opposite sides, of a locking bar extending 20 transversely of the frame and key levers beneath the key levers to lock the latter, and projecting through said openings and supported directly by the frame at said openings, said bar arranged to be withdrawn 25 lengthwise to release the key levers, and means to seal the locking bar against removal.

6. The combination with a frame and a key-lever mechanism contained therein comprising a set of key levers ranged across 30 the frame, said frame having openings in its opposite sides, of a locking bar extending across the frame and key levers directly beneath and close to the key levers to lock the 35 latter and extending into said openings and supported by the frame at said openings, said bar movable lengthwise to withdraw it from beneath the key levers, and means to seal said locking bar against manipulation 40 or withdrawal.

7. The combination with a frame and a key-lever mechanism contained therein comprising a set of key levers ranged across the frame, said frame having openings in its 45 opposite sides, of a locking bar extending across the frame and key levers beneath and close to the key levers to lock the latter, said bar being of a form to rest upon the edges of the openings in the frame, and to fit under 50 the keys to prevent manipulation of the latter, said bar movable in the direction of its length to withdraw it from the frame.

8. The combination with a frame and a key-lever mechanism contained therein comprising a set of key levers ranged across the frame, said frame having openings in its 55 opposite sides, of a locking bar extending across the frame and key levers beneath the key levers to lock the latter, said bar extending through said openings and being of a form to rest upon the edges of the openings, and to fit under and close to the keys to prevent manipulation of the latter, said bar having at one end a fluke or cross-piece 60 to prevent it from being drawn through the

adjacent opening and having at the other end a padlock too large to go through the other opening in the frame.

9. The combination with a frame and a key-lever mechanism contained therein comprising a set of key levers ranged across the frame, said frame having openings in its opposite sides, of a locking bar extending across the frame and key levers beneath the key-levers to lock the latter, said bar extending through said openings and being of a form to rest upon the edges of the openings, and to fit under the keys to prevent manipulation of the latter, said bar having at one end a fluke or cross-piece to prevent it from being drawn through the adjacent opening, and having at the other end a projection provided with an opening in which is inserted the hasp of a padlock, said padlock being too large to go through the other opening in the frame.

10. The combination with a frame and a key-lever mechanism contained therein, said frame having openings in its opposite sides, of a locking bar extending through 70 said openings beneath the key-levers to lock the latter, said bar being of a form to rest upon the edges of the openings in the frame, and to fit under the keys to prevent manipulation of the latter, said bar having at one end a fluke or cross-piece to prevent it from being drawn through the opening, and having at the other end a padlock too large to go through the opening in the frame, said bar made of wood, and having at one end a 80 sheet metal ferrule upon which is formed 85 said fluke.

11. The combination with a frame and a key-lever mechanism contained therein, said frame having openings in its opposite sides, 90 of a locking bar extending through said openings beneath the key-levers to lock the latter, said bar being of a form to rest upon the edges of the openings in the frame, and to fit under the keys to prevent manipulation of the latter, said bar having at one end a fluke or cross-piece to prevent it from being drawn through the opening, and having at the other end a padlock too large to go through the opening in the frame, said 95 bar made of wood, and having at one end a sheet metal ferrule upon which is formed 100 said fluke, and having at the other end a sheet metal ferrule through which an opening is made for the hasp of the padlock.

12. The combination with a frame and a key-lever mechanism contained therein comprising a set of key levers ranged across the frame, said frame having openings in its opposite sides, of a locking bar extending 110 across the frame and key levers directly beneath and close to the key-levers to lock the latter, and means to seal said locking bar against manipulation or withdrawal; said 115 bar being of a form to rest upon the edges 120 of the openings in the frame.

of the openings in the frame, and to fit under the keys to prevent manipulation of the latter.

13. In a typewriting machine, the combination with the machine frame, of a set of type actions comprising types and keys actuated thereby, said type actions being ranged across the machine, and a locking bar extending transversely of said type actions in their path of movement, whereby they are locked against operation, said locking bar being supported at its ends in the machine frame and movable lengthwise to release the type actions.

14. In a typewriting machine, the combination with the machine frame, of a set of type actions comprising types and keys actuated thereby, said type actions being ranged across the machine, a locking bar extending transversely of said type actions in their path of movement, whereby they are locked against operation, said locking bar being supported at its ends in the machine frame and movable lengthwise in one direction from locking position to release the type actions, a lock to normally prevent said movement of the locking bar, and means to prevent said bar from being moved lengthwise in the opposite direction from said locking position.

15. In a typewriting machine, the combination with the machine frame, of a set of depressible key levers ranged across the machine, and a locking bar extending across the machine and said levers directly beneath the levers in position to lock them against operation, said frame having open-

ings in which the ends of the locking bar are supported, said bar having a broad flat key-engaging surface, whereby said surface underlies a considerable length of each key lever, said bar and openings being of a form to prevent the bar from being rotated into position to release the keys, said bar movable in the direction of its length to withdraw it from locking relation to the keys.

16. In a typewriting machine, the combination with the machine frame, of a set of depressible key levers ranged across the machine, a locking bar extending across the machine and said levers directly beneath the levers in position to lock them against operation, said frame having openings in which the ends of the locking bar are supported, said bar having a broad flat key-engaging surface, whereby said surface underlies a considerable length of each key lever, said bar and openings being of a form to prevent the bar from being rotated into position to release the keys, said bar movable in the direction of its length to withdraw it from locking relation to the keys, a barb on one end of the bar to engage the machine frame and prevent the bar from being withdrawn in one direction, and a lock connected to the other end of the bar to normally prevent it from being withdrawn in the opposite direction.

ALFRED G. F. KUROWSKI.
